GERMANY.

TELEPHONE SYSTEM.

1,259,862.

Specification of Letters Patent. Patented Mar. 19, 1918.

Application filed October 25, 1916. Serial No. 127,554.

To all whom it may concern:

Be it known that I, WILLI HERRMANN, engineer, a subject of the Emperor of Germany, residing at and whose post-office address is Colonnenstr. 29, Berlin-Schöneberg, Germany, and I, OTTO STRITTER, engineer, a subject of the Emperor of Germany, residing at and whose post-office address is Papestr. 24, Lichtenrade, Germany, have invented certain new and useful Improvements in Telephone Systems; and we do hereby declare the following to be a full, clear, and exact description of the invention, such as will enable others skilled in the art to 15 which it appertains to make and use the same.

Our invention refers to telephone, telegraph or electric signaling systems and more especially to a method of and apparatus for 20 selecting and calling up stations which are connected to lines common to all of them, by means of controllers moved step by step.

Systems of this kind generally use a controller which is moved until its hand reaches 25 the sign or figure indicating the desired station. In this position of the hand the alarm of the desired station only is connected with the source of calling current of the calling station, this latter station thereupon effecting the call by special means. 30 This way of selecting and calling is, however, very cumbersome and takes too long for the reason that, in selecting the desired station, care must be taken that the hand of

35 the controller at the calling station is not moved past the sign or figure of the desired station; on the other hand in order to throw in the calling signal on the desired station, a key or the like has to be operated. The 40 inconvenience first spoken of is material in practice, as it happens frequently that the proper indication on the controller at the calling station is passed and the movement of the controller has then to be continued 45 for substantially a full turn in order to carry the hand back again.

The present invention does away with 50 these inconveniences in such a way that merely the generator or another source of current at the calling station need be cut in, while all the rest, such as stopping the selecting operation, throwing in the call signal on the desired station, and eventually carrying the controllers back to their position of rest is effected automatically in the

sense that aside from throwing in the source of calling current there is nothing else to be done.

The present invention may be applied to various kinds of telephone, telegraph and 60 like systems and, as a practical matter, is independent of the kind of apparatus used at the stations.

In the drawings affixed to this specification and forming part thereof the present 65 invention is applied, as an example, to a telephone system. In these drawings,

Figures 1 and 2 show two different modifications of such a system in a diagrammatic way; Fig. 3 is a vertical cross-section of a 70 controller for use with the systems; Fig. 3^a is a perspective view of the electromagnet; Fig. 4 is a front view of the controller; and Fig. 5 is a detail, on an enlarged scale, of a modified form of shaft. 75

For the sake of simplicity, there is shown in Fig. 1 a telephone system comprising but two stations A and B, each provided with a controlling device *s*, such as is shown in Figs. 3 and 4. In this controlling device an 80 electromagnet *e* (Fig. 3^a) causes a shaft *x* to be rotated by a pawl and ratchet arrangement, the contact springs, *f*, *f*² and a contact piece *f*' rigidly fixed to said shaft being thus moved step by step simultaneously with a hand *i* mounted in front of a dial *z* (Fig. 4). For the sake of simplicity, shaft *x* has been represented in Fig. 1 in 85 two parts.

At each station, contact spring *f*' is fastened to shaft *x* in such manner that only the one at the station indicated by the hand *i* contacts with pin *f*². Each controller *s* is provided with a detachable plug *t* adapted to be inserted optionally into the holes *o* 95 which are provided in accordance with the number of sub-stations. Whenever spring *f*, in being moved, engages the inserted plug *t*, it is disengaged from its spring *f*³. The electrical connection of the movable springs 100 *f*, *f*², *f*' is effected, as shown in Fig. 3, by brush collectors *f*⁴.

In Fig. 1, *w* is a call alarm, *h* a telephone hook switch and *c* a generator. The telephone hook switch *h* is adapted to interrupt 105 the circuit at the contact *m* whenever the receiver is lifted off, the transmitter being thrown in at the same time. Upon rotating the generator *c*, the contact springs *k*, *l* are connected with contacts *n*, *p*, as a result of 110

the fact that the handle is then moved axially to the right for rotation and pulls the arms *k* and *l* over with it.

The mode of operation of this device is 5 as follows:

Whenever the subscriber of sub-station A desires connection with sub-station B, he inserts plug *t* in the hole *o* provided for that sub-station, and turns the generator *c*. The 10 calling current then flows through the electromagnets *e* of all the sub-stations, through *c*, *p*, *l*, *l*, *f*, *f*³, *2*, *k*, *n*, *3*, and thence through *a* to *4*, *e*, *5* and *6*, of all sub-stations, back through *b* and *7* to *c* of the calling station. In 15 consequence thereof the contact springs *f*, *f*², *f*³ of all sub-stations are simultaneously and equally moved step by step until the hands *i* reach B, the figure corresponding to sub-station that is being called. Spring *f* at the 20 calling station A then engages the plug *t* inserted there and is disengaged from its spring *f*³. This causes the generator current to be cut off from the electromagnets *e* of all the sub-stations and the controllers *s* to 25 be stopped. However, as the contact spring *f*² at sub-station B is then in contact with pin *f*², the calling current from generator *c* flows through the call alarm *w* of sub-station B by way of *c*, *p*, *l*, *l*, *f* and *t*, and then 30 through the ground from sub-station A to B, where it passes through *f*², *f*³, *8*, *w*, *9*, *m*, *10* and *6*, and thence back to generator *c* at sub-station A through *b* and *7*. As soon as 35 the subscriber of sub-station B has answered the call, by lifting the receiver off the hook switch *h*, the circuit at contact *m* is interrupted, thereby disconnecting his call alarm *w* and connecting in his transmitter and receiver. After the conversation is over, the 40 controllers *s* may be returned to their initial position in any suitable manner.

Another arrangement for selecting and calling a sub-station in accordance with the present invention is shown in Figs. 2 and 5. 45 A groove *V* is provided in the shaft *x* of each controller *s*, and a ball or roller *g* at the end of extension *q* of pivoted lever *u* enters the end *v* of the groove when the shaft *x* is momentarily retarded or braked with the 50 two in registry. The openings *v* of shafts *x* in the several sub-stations are disposed in such manner that only the one in the sub-station called stops in registry with the ball *g*. As long as the ball *g* runs in the groove, 55 the contact at 11 is closed. When the shaft *x* has been turned around once, the ball *g* leaves the groove at *y* and as soon as it has reached the surface of shaft *x*, the hand *i* at the same time reaching its position of 60 rest, the contact at 11 is opened again. For the remaining apparatus of the sub-stations C and D, the same reference letters as for the stations A, B have been used in Fig. 2.

The operation of this latter system is 65 similar to the one mentioned above.

In order for subscriber C to call subscriber D, plug *t* at sub-station C is inserted in the corresponding hole *o* and generator *c* is turned. The electromagnets *e* of all sub-stations are fed with current by way of *c*, 70 12, 13, and 14, where the current divides, one part passing through 15, *e*, 16, *b* and 17 back to *c* of sub-station C, and the other part passing through 25, *f*, *f*³, 24 and 23 to *a*, and thence through the electromagnets of 75 all sub-stations by way of 22, 21, *f*³, *f* 20, 19, *e* and 18, and back through *b* to sub-station C. When the hand *i* reaches the figure corresponding to sub-station D, spring *f* at sub-station C engages the inserted plug *t*; 80 at the same time the ball or roller *g* of lever *u* in sub-station D registers with the end *v* of groove *V*. Plug *t* disengages springs *f* and *f*³, and in consequence thereof the controller *s* at sub-station D is cut out and 85 stopped. The ball or roller *g* at sub-station D is thereby permitted to enter the opening *v* of the groove, which might not occur if shaft *x* was turned without retardation at this position. However, the retardation of 90 controller *s* at sub-station D is only momentary, electromagnet *e* at the calling station C not having been cut out. Upon rotating the generator *c* further, controller *s* at sub-station C continues its movement, spring *f* 95 slides over *t* and again comes in contact with spring *f*³, thus reestablishing the circuit to electromagnet *e* of sub-station D; or, if desired, the plug *t* at sub-station C may be moved to its initial position when the hand *i* points to D, thereby reestablishing the circuit to electromagnet *e* of sub-station D by way of springs *f*, *f*³ of sub-station C, as before. In consequence thereof, the controller *s* at sub-station D is again moved along, the 100 ball *g* then running in groove *V* and holding the circuit of contact 28 closed. The alarm *w* at sub-station D is thus actuated by way of *c*, 12, 13, 14, 25, *f*, *f*³, 24, 23, *a*, 22, 29, 11, 28, *u*, 27, *w* and 26, and thence back through 105 *b* and 17 to *c*. The generator *c* at sub-station C is turned until the controllers *s* have returned into their initial position. In this position the ball or roller *g* of sub-station D again rests on the surface of shaft *x* and in 110 consequence thereof contact 28 is interrupted and the alarm *w* of station D is cut out. The return movement of controller *s* of the calling station caused to take place by reason of this mode of operation is balanced by 115 a synchronizing device supposed to be well-known and therefore not shown in the drawings.

We claim:

1. The method of selecting and calling up 125 telephone or telegraph stations connected to common lines by aid of step by step switches, which consists in utilizing the movements of the switches to automatically change the path of the calling current at the station 130

- called up in such a way that the call alarm at this latter station is immediately actuated, and thereafter utilizing the calling current to return to their positions of rest 5 the switches at the station called up.
2. The method of operating a telephone system, which consists in simultaneously interrupting the movement of the switches or controllers at all the sub-stations by aid of 10 a preliminary operation effected at the corresponding point of the switch or controller of the subscriber calling the other sub-station up, and automatically throwing in the call alarm of the called-up station in the 15 place of the switch or controller at that station.
3. The method of operating a telephone system, which consists in causing all the subscriber switches or controllers with the only 20 exception of the calling station to be temporarily stopped by a preliminary operation effected on the corresponding point of the controller of the calling station, thus causing the alarm on the called-up station 25 to be thrown in until all controllers have returned to their position of rest and utilizing the current serving for operating the alarm to return all the controllers to their position of rest.
- 30 4. In a telephone system, in combination, a plurality of sub-stations connected to common lines, a step by step switch or controller on each sub-station, connections between each controller and all sub-stations, means

for bringing each controller in connection 35 with a single sub-station and means for automatically changing over the call current at the point of the controller which has been set for a certain station.

5. In a telephone system, in combination, 40 a plurality of sub-stations connected to common lines, a step by step switch or controller on each sub-station, connections between each controller and all sub-stations, means for bringing each controller in connection 45 with a single sub-station, means for automatically changing over the call current at the point of the controller which has been set for a certain station, and means for preventing the controller from passing beyond 50 the desired position and for automatically interrupting the controller movement and throwing in the alarm of the desired sub-station.

6. In a telephone system, in combination, 55 a plurality of sub-stations connected to common lines, a controller in each sub-station connected with all sub-stations and means for temporarily retarding the movement of all the controllers excepting the one operated to call up the desired station. 60

In testimony whereof we affix our signatures, in presence of two witnesses.

WILLI HERRMANN.
OTTO STRITTER.
